STRIP FEEDING AND SEVERING APPARATUS

John Quirk Sherman, deceased, late of Dayton,
Ohio, by Katherine M. Sherman, William C.
Sherman, and Wellmore B. Turner, executors,
all of Dayton, Ohio

Application May 3, 1941, Serial No. 391,782

25 Claims. (Cl. 101—227)

This invention relates to printing apparatus, and more particularly to automatic mechanism for printing form letters, circulars and the like, employing therefor continuous web or series connected stationery which, after the printing operation, is automatically sub-divided into successive sheets.

The present apparatus is designed for use in mercantile and industrial establishments for rapidly multigraphing letters, bills and circulars, for which continuous web printed stationery in roll or packet form shall have been previously prepared, although it may be employed for general type printing of hand bills, circulars and forms.

The web of stationery is preferably pre-printed with a succession of letterheads at spaced intervals, forms or other indicia, in predetermined relation with which successive letter print impressions are to be effected.

A continuously rotating drum carries the printing type, which may be either directly inked or operate through an overlying inked ribbon to effect an impression in a manner similar to the well-known multigraphing machines. While the printing cylinder, of which only a small portion of the periphery may be occupied by printing type, rotates continuously, the paper feeding mechanism is operated intermittently through step-by-step movement, the length of the steps being variable in accordance with the size of the desired printed sheet. Paper feeding devices of positive character are employed, which preferably, though not necessarily, are of the pin wheel type, the pins of which progressively engage in spaced marginal holes in the paper web. Subsequently to the printing operation the punched margins of the printed web are trimmed off and the web is transversely cut intermediate succeeding impressions into printed sheets.

The object of the invention is to simplify the construction as well as the means and mode of operation of continuous web severing apparatus, whereby it will not only be cheapened in construction, but will be more efficient in operation, automatic in action, rap'd, accurate and uniform in production of printed material, and unlikely to get out of repair.

In some instances it is desired that the final record sheets after separation, be of a size which is not divisible into the periphery of the printing cylinder from which the web has been printed. Sometimes for other reasons the lengths of final separated sheets do not agree exactly with the spacing of successive printed areas on the web, and it is necessary to remove a waste area be-

tween successive impressions, and the final individual sheets containing the impressions. In the event of zigzag folded packs wherein it is customary to divide the web or strip on transverse weakened division lines coincident with the folds, it is sometimes desirable to afford clean sharp edges on the severed sheets by cutt'g in offset relation at opposite sides of the fold line. This is particularly true when printing checks, drafts or other papers. In either event it is highly desirable that the web or strip be maintained intact until all entries and typed or imprinted inserts have been made, and then the strip severed and the lengths of the severed portions reduced as a final operation.

Wherefore, the present disclosure is directed to severing means and the mode of operation for making plural cuts intermediate succeeding imprinted areas.

20 A further object of the invention is to provide in a web feeding apparatus severing means repetitiously operable at succeeding differently spaced intervals to sever the web or strip into portions of different length.

25 A further object of the invention is to provide in a web feeding apparatus, severing means for simultaneously severing the web on relatively spaced parallel lines.

30 A further object of the invention is to provide in a web feeding apparatus timing means for a web severing device by which the severing device is operated in timed sequence to sever from the web succeeding portions of different lengths.

35 A further object of the invention is to provide in a web severing apparatus having the advantageous structural features and inherent meritorious characteristics and the mode of operation herein set forth.

With the above primary and other incidental 40 objects in view as will more fully appear in the specification, the invention consists of the features of construction, the parts and combinations thereof and the mode of operation, or their equivalents, as hereinafter described and set forth in 45 the claims.

Referring to the accompanying drawings, wherein are shown the preferred but obviously not the only form of embodiment of the invention.

50 Fig. 1 is a side elevation of the assembled apparatus.

Fig. 2 is a top plan view thereof.

Fig. 3 is an enlarged detail sectional view on the longitudinal medial line looking upwardly in

55 Fig. 2.

Fig. 4 is a plan view of a fragmentary portion of a continuous record web or strip showing succeeding portions severed therefrom by the presently described apparatus and method.

Fig. 5 is a plan view of an adjustable strip severing portion of a modified apparatus.

Fig. 6 is a side elevation of the portion of the apparatus shown in Fig. 5.

Fig. 7 is a detail view of a further modification of the apparatus shown in Figs. 5 and 6 for effecting double cut operation at each actuation.

Like parts are indicated by similar characters of reference throughout the several views.

The apparatus forming the subject matter hereof, as illustrated in the drawings, is mounted upon and between parallel side frames 1-1 mounted upon a base 2 and interconnected at spaced intervals by suitable tie bars.

The web of continuous series connected stationery is supplied from a roll 3 journaled on the frame 1 at one end of the apparatus from which the web passes over a guide roll 4, thence over a guide table 5 and between the printing cylinder 6 and a coacting platen 7 having operating contact through a suitable opening in the table.

Beyond the printing cylinder the web passes beneath a signature imprinting roll 8, which may, however, be employed for other printing impressions in differently colored ink or in locations upon the web outside the impression area of the printing cylinder 6. Continuing its course over the table 5, the marginally punched web is engaged by pin wheel feed devices 9 by which the web is positively advanced through successive movements proportionate to the length of the finished sheets, the extent of which is variable at will.

The impression contact of the printing area of the rotating cylinder 6 with the paper against the platen roll 7 would ordinarily be sufficient to insure unison travel of separate sheets of paper web when properly fed so long as the impression contact is maintained on a single form. It is desired, however, to advance a paper web drawn from a roll of continuous forms a selected predetermined distance at each operation sufficiently to compensate for the portion of the sheet occupied by the letterhead and a suitable space at the end and preceding the imprinted matter to afford to the printed letter or form a presentable balanced appearance and uniform length. This feeding motion of the paper web therefore varies in extent according with the size of the ultimate printed sheet, the extent of the letterhead area and that used for "balancing" the imprint material on the sheet. Any slight differential or error of the feeding movement which would be quite unnoticeable on sheets singly fed would be accumulative on continuous web material, and after a few impressions such differential would become quite serious.

In order to secure accurate registry upon succeeding sheets, it is therefore necessary that the advance of the material intermediate the impression periods be quite accurately effected. Hence the use of positive pin wheel feed devices 9 is preferred.

After having served its purpose of accurately and uniformly feeding the paper web, the punched margins thereof are trimmed off by being passed under rotary cutters 10, and finally the printed web, minus its punched margins, is transversely divided at regular spaced intervals by a pair of "chopper" type cutters 11 and 11'.

Power is applied through the main drive shaft

12 (beneath the printing cylinder) which carries a gear pinion 13 meshing with a corresponding pinion 14 upon the platen roll 7. The platen roll pinion meshes with a large gear wheel 15 fixedly connected to the printing cylinder 6 and rotating in unison therewith. The printing cylinder is thus given continuous rotary motion, always in the same direction.

The rotary printing drum is operatively connected through a train of idler gears 35, 36, 37, 38, 39 and 40 with a gear wheel 41 upon a shaft 42 carrying the pin wheel feed devices 9 to which intermittent motion is thus transmitted. By this means the paper web is advanced uniformly with the rotation of the printing cylinder while the printing form is in contact therewith, and is further advanced in unison with the rotation of the cylinder either before or after the engagement therewith of the printing form, but such unison movement is not continuous and the paper web comes to rest while the cylinder continues to rotate to present the type form in position for the succeeding printing impression upon the web.

25 The peripheral pins of the pin wheel feed devices 9 project through registering slots in the feed table 5 into feeding engagement with the marginal holes in the paper web. The feed table is preferably divided and the section contiguous to the pin wheels is pivotally mounted to afford access to such wheels. The web is maintained in feeding engagement with the pins by an overlying keeper plate 43, which is slotted at 44 for the passage of the feeding pins in their rotary travel. The keeper plate 43 is carried upon swinging arms 45 pivoted at 46, one of which is provided with a peripherally notched head 47 for engagement of a detent 48 by which the keeper plate is supported in slightly elevated relation above the feeding table 5 to minimize friction. The pivotal mounting of the keeper plate enables it to be turned to an inoperative position to facilitate insertion and initial adjustment of the paper web upon the pin wheels 9.

45 Located beyond the feeding wheels 9 are parallel spaced trimming discs 10 cooperating with a platen roller 50, between which the paper web advances, and by which the punched margins of the web are simultaneously trimmed off. The 50 cutters or trimming discs 10 are adjustably mounted on swinging arms 51 and adjusted relative to the platen roll by the adjusting screw 52. Idler rollers 49 are mounted adjacent to the trimming discs 10 and hold the paper web on the platen 50.

55 Finally the advancing paper web is engaged by a transverse cutter, by which it is divided at spaced intervals into succeeding separate sheets, each of which bears the imprint of the type or 60 marking devices carried by the printing cylinder in accurately predetermined position upon the sheet, which may also bear a previously printed letterhead or other data or indicia.

The transverse cutter may be of various forms. 65 A quite simple construction consists of a stationary cutter bar 53 mounted upon the main frame, with which cooperates sweeps 54 and 54' carrying coacting transverse cutter bars 11 and 11'. Such sweep arms are adjustably carried 70 upon the revoluble shaft 56 upon which is mounted a driven gear 57, to which motion is transmitted by idler gears 58 and 49 forming a continuation of the gear train operating the pin wheel feed devices. Being operated through the same driving train, the cutters function in timed

relation with the web feeding devices. Sheets of different length are accommodated by adjusting the sweep arms to different radial positions about the shaft, thereby changing the timed relation of the cutter knives. In such construction one cutter blade severs the imprinted sheet from the web and the second blade trims the intermediate portion from the advance end of the web.

The preferred form of cutter comprises a head 60 slidably mounted upon guide rods 61 supported in a cross bar 62 of the main frame and projecting longitudinally therebeyond. The guide rods are preferably provided with rack teeth 63 for engagement of pinions carried by the head and rotatable by the crank 64 to slidably adjust the cutter head. Mounted in the cutter head 60 is a vertically sliding knife bar 65 carrying a cutter blade 66, the cutting edge of which is upturned for cooperation with a second knife 67 stationarily carried upon the head 60. The paper web is progressively advanced between such knives. The sliding knife bar 65 is normally held retracted by a spring 68 and is guided between the rear side of the head 60 and an adjustable bearing or guide plate 69 mounted upon the head. The movable knife 66 has an upwardly projecting guide or lead finger 70 overlapping the end of the stationary knife 67 to insure proper sliding relation therebetween.

The sliding knife 66 is actuated against the tension of its retracting spring by a pivoted lever plate 71 engaging with a stud 72 on the knife bar 65 and in turn oscillated by a bell crank lever 73. The bell crank lever is connected by a link 74 with a rock arm 75 slidably adjustable on a rock shaft 76 extending longitudinally of the machine. At its opposite end the rock shaft carries a similar rock arm 77, connected by a similar link with a small cam arm 78, which is engaged by roller studs 78a upon the cam 79 at each rotation of the cam which actuates the gear sector 23, thereby transmitting to the shaft 76 intermittent rocking motion. The shaft and rock arm 75 are splined for relative adjustment longitudinally of the shaft in unison with the adjustment of the cutter head 60, as may be necessary to accommodate sheets of different sizes. The links 74 are provided with double pivotal or universal joints to enable them to compensate for rocking motion of the respective connected arms in different planes.

The roller studs 78a being relatively close together, the shaft 76 is actuated twice in rapid succession. A second cutting operation is thereby performed on the strip by the blades 66-67 in close proximity to the location of the first cut, the strips having been advanced intermediate the cutting operations. In such construction, the first cut severs the imprinted sheet from the strip and the second cut severs a relatively small portion intermediate the imprinted sheets from the advance end of the strip.

In lieu of the two roller studs 78a, a single stud may be used, in which case there is added to the cutter head 60 a second pair of cooperating blades 66'-67' which operate in synchronism with the blades 66-67 as shown in Fig. 7. This construction enables the strip to be severed at relatively spaced positions simultaneously.

In printing form letters it is quite desirable to imprint a facsimile signature in differently colored ink, or it is sometimes desirable for emphasis to print "fill-ins" of different color. For this pur-

pose there is provided an auxiliary printing mechanism.

The continuously rotating cylinder gear 15 intermeshes with an idler pinion 84 transmitting motion to a gear 85 upon a transverse shaft 86, upon which is mounted for rocking motion an eccentric sleeve 87. Journaled upon the eccentric sleeve 87 is the auxiliary printing roller 8, bearing impression plates or type as may be required. The printing roller is operatively connected with the drive shaft 86 for unison rotation.

The gear train is so proportioned that the printing roller may make several rotations in its inoperative position before being lowered into impression making contact by actuation of the lever 94 and makes but one rotation therein before being returned. The printing roller is supplied with ink from a roller pad 87 by a transfer roller 98 driven through the gear pinions 99-100 and 101 from the auxiliary printing roller shaft 86.

In lieu of marginally punched paper as before described, the paper web may be medially punched at spaced intervals, as shown at 113 in Fig. 4, for engagement of feeding devices.

The use of the present apparatus enables the rapid, accurate and economical production of individual multi-form letters, circulars and other printing operations. By employing stationery pre-printed in roll form, a great saving in material and printing costs is effected. The present apparatus accurately positions its impressions in relation with the severing position and the positive paper feeding means automatically and continuously maintains such relation.

It is to be noted that during successive contact pressure engagements of the strip of material between the imprinting drum 6 and platen roller 7, which ordinarily continues throughout a portion only of the rotation of the drum 6, the strip is subject to intermittent frictional feeding impulses, and that the pin wheel 9, located in offset relation with the frictional feeding members 6 and 7, in the direction of advancement of the strip, maintains continuous feeding engagement with the strip to continue advancement of the strip intermediate succeeding intervals of frictional feeding influence by the rollers 6 and 7. Thus the intermittent frictional feeding operations of the rollers 6 and 7 alternate with positive pin type feeding operations of the pin wheel 9 which occur independently of the feeding influence of the rollers 6 and 7. During a portion of each cycle of operation the strip is subjected to simultaneous frictional and positive pin type feeding operations and during the remainder of the cycle of operation, intermediate succeeding frictional feeding operations, the strip is subject to only positive pin type feeding operation.

The present application is a continuation in part of application Serial No. 115,804, filed December 14, 1936, now matured into Letters Patent No. 2,177,675, of which a divisional application Serial No. 294,199 has now matured into Letters Patent No. 2,252,735, issued August 19, 1942.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described the invention, what is claimed is:

1. In a strip severing apparatus, wherein a continuous strip of series connected longitudinally spaced imprinted forms is divided into individual imprinted sheets disproportionate to the spacing of the imprinted forms upon the strip, including a feeding device for progressively advancing the continuous strip of material, severing means relative to which the strip is advanced engageable therewith for transversely severing the strip, and actuating means for operating the strip severing device repetitively intermediate succeeding printed forms of the strip in synchronism with the strip feeding device, the construction and arrangement being such that the strip is reduced to individual printed sheets of less length than the proportionate spacing of the imprinted forms upon the strip.

2. In an apparatus of the character described, wherein a continuous strip of series connected longitudinally spaced printed forms is divided into a succession of individual sheets, the length of which is disproportionate to the spacing of the imprinted forms upon the strip, including strip feeding means, strip severing means and actuating means operative to doubly sever the strip transversely intermediate succeeding printed forms thereof for operating the strip feeding and strip severing means in timed relation, the construction and arrangement being such that the strip is progressively divided into alternate printed sheets of less length than the spacing of the forms and transverse strips of waste material.

3. In an apparatus of the character described, printing mechanism for imprinting legends upon a continuous strip of material in longitudinally spaced relation leaving intermediate areas of the strip therebetween, strip feeding means for progressively advancing the strip past a severing position, and strip severing means operative to remove from the areas of the strip intermediate succeeding imprinted legends relative narrow transverse strips thereby separating the initial strip into a succession of individual sheets.

4. The herein described method, consisting in imprinting legends upon a continuous strip of material in longitudinally spaced areas thereof, and thereafter severing the imprinted strip into printed sheets of less length than the spacing of the printed forms upon the strips by removing transverse strips of material from between succeeding imprinted areas of the original strip.

5. In an imprinting and severing apparatus, wherein a continuous strip of material having longitudinally spaced holes therein is imprinted within longitudinally spaced areas and the imprinted areas subsequently divided into separate sheets, including a feeding device for advancing the strip past printing and severing positions, imprinting mechanism for imprinting the strip intermediate succeeding longitudinally spaced holes, and severing means operative to remove from the strip areas thereof intermediate

succeeding imprinted impressions containing the longitudinally spaced holes, whereby the strip is divided into a succession of imprinted sheets.

6. An imprinting and severing apparatus, wherein a continuous strip of material having longitudinally spaced holes is imprinted at longitudinally spaced intervals and subsequently divided into separate sheets, imprinting mechanism for imprinting the strip at successive relatively spaced intervals, and severing means operative to simultaneously remove from the strip an imprinted portion thereof and a transverse strip intermediate the severed and next succeeding portion.

7. An imprinting and severing apparatus, wherein a continuous strip of material is imprinted at longitudinally spaced intervals and subsequently divided into individual sheets, imprinting mechanism for imprinting the strip in predetermined relatively spaced intervals, and severing means operative to sequentially remove from the strip succeeding imprinted portions thereof, and transverse strips intermediate the succeeding imprinted portions.

8. A strip severing device, wherein a continuous strip of series connected stationery bearing a succession of longitudinally spaced printed legends is divided into individual printed sheets, feeding means therefor, relatively spaced cutters past which the strip is advanced by the feeding means, actuating means for simultaneously operating the cutters, the construction and arrangement being such that cutters are actuated in timed sequence with the advancement of the strip to simultaneously sever the strip on relatively spaced transverse lines into a printed sheet and a transverse strip of waste material.

9. A strip severing device, wherein a strip of series connected printed form stationery having therein longitudinally spaced strip control configurations intermediate succeeding printed forms is advanced into strip severing position for division into separate printed sheets, feeding means for advancing the strip alternating longer and shorter distances between succeeding severing operations, strip severing means actuated in timed sequence with the feeding means for successively removing from the strip transverse areas thereof containing the strip control configurations, the construction and arrangement being such that the strip is divided into a succession of individual printed sheets devoid of such configurations.

10. The herein described method of severing a continuous strip of material having printed portions disposed at relatively spaced intervals, including the steps of severing a printed portion from the advance end of the strip, and thereafter severing from the advance end of the strip an unprinted portion immediately preceding the next printed portion.

11. In a strip severing apparatus, wherein a continuous strip of series connected printed form stationery is zigzag folded into a supply packet and advanced from such supply packet past strip severing positions and divided into separate printed sheets, a strip feeding device therefor relatively spaced strip severing positions past which the strip is advanced, strip severing means and actuating means therefor by which the strip severing means are simultaneously operative to divide the strip into a plurality of separate printed sheets.

12. A strip severing apparatus, wherein a strip of continuous printed form stationery is divided

alternately into alternating printed sheets and waste portions of different length, feeding means therefor, strip severing means past which the strip is advanced by the feeding means, actuating means for the severing means operative in timed sequence with the feeding means, and adjusting means for enabling variation of the length of the printed sheets without changing the size of the alternate waste portions removed from the strip.

13. A strip severing apparatus, wherein a strip of continuous form stationery is divided into succeeding portions of different extent, feeding means therefor, strip severing means past which the strip is advanced by the feeding means through alternating longer and shorter distances between succeeding severing operations, and actuating means for the severing means operative in timed sequence with the feeding means, the construction and arrangement being such that the apparatus is adapted to sever from the strip alternate portions of longer and shorter length.

14. A strip severing apparatus, wherein a strip of continuous form stationery is simultaneously divided into different length portions, feeding means for advancing the strip equal distances intermediate succeeding severing operations, relatively spaced severing positions past which the strip is advanced, strip severing means, and actuating means therefor operative in timed sequence with the feeding means, the construction and arrangement being such that the strip severing means are simultaneously operative to divide the strip into a plurality of different length portions at each severing operation.

15. A strip severing apparatus, wherein a strip of continuous form stationery is simultaneously divided into different length portions, feeding means for advancing the strip equal distances intermediate succeeding severing operations, relatively spaced severing positions past which the strip is advanced, strip severing means, actuating means therefor operative in timed sequence with the feeding means, and means for varying the length of at least one of the plurality of different length portions simultaneously severed from the strip.

16. A strip severing apparatus, wherein a continuous strip of series connected printed form stationery folded in zigzag formation is advanced from a supply packet thereof and progressively divided into printed sheets of less length than the folds of the zigzag folded strip supply packet, including a strip feeding device, strip severing means relative to which the strip is advanced, and actuating means for repetitiously operating the strip severing means intermediate during the advancement of each fold length past the severing position in synchronism with the advancement thereof to sever the strip into individual printed sheets of less length than the folds of such packet.

17. The herein described method of progressively dividing a continuous web of series connected longitudinally spaced printed forms having therein a succession of longitudinally spaced locating holes intermediate succeeding printed forms into a succession of individual printed sheets of prescribed size, progressively advancing the strip prescribed distances intermediate succeeding severing operation and synchronizing the advancement of the strip with the severing operation by means of said holes, and doubly severing the strip intermediate succeeding printed forms at opposite sides of the holes and thereby

removing from the supply strip a series of transverse waste strips containing the holes.

18. The herein described method of progressively dividing a continuous web of series connected longitudinally spaced printed forms having therein a succession of longitudinally spaced holes into a succession of individual printed sheets of prescribed size and simultaneously removing the portions containing the holes therefrom, including advancing the web in timed relation with the operation of a severing device, and utilizing the holes to position succeeding portions of the web in severing relation, doubly severing the strip intermediate succeeding printed forms to shorten the resulting sheets relative to the spacing of the printed forms and removing the areas containing the holes in synchronism with the advancement of the web.

19. A strip severing apparatus, wherein a continuous strip of longitudinally spaced series connected printed forms is divided into a succession of individual printed sheets of less size than the original spacing of the printed forms upon the strip, including strip feeding means for progressively advancing the strip relative to severing position, control means for registering prescribed areas of the strip successively in severing position and severing means for transversely dividing the web on succeeding relatively spaced lines intermediate succeeding imprinted forms.

20. The herein described method of progressively dividing a continuous printed web of series connected longitudinally spaced printed forms into a succession of individual printed sheets, including progressively advancing the strip relative to a severing position in timed relation with successive severing operations, transversely dividing the web intermediate succeeding relatively spaced imprinted forms thereon and reducing the length of the resulting imprinted sheets in synchronism with the advancement of the web.

21. The herein described method, including printing a succession of legends upon a continuous strip of material at uniformly spaced intervals, and dividing the strip into a succession of sheets of less length than the relative spacing of the legends, including doubly severing the strip transversely on relatively spaced parallel lines intermediate succeeding imprinted legends.

22. The herein described method, including printing a succession of legends upon a continuous strip of material at uniformly spaced intervals, reversely folding the strip into zigzag formation upon fold lines intermediate succeeding legends, dividing succeeding folds of the strip one from another and shortening the divided folds to afford legend bearing sheets of less length than the folds of the zigzag formation of the strip.

23. An apparatus for dividing a continuous strip of record material having thereon a succession of longitudinally spaced printed forms into a series of individual printed forms, including strip feeding means for advancing the strip to present successive form lengths thereof in strip severing position, severing means for doubly severing the strip intermediate succeeding imprinted forms thereof to afford a series of printed sheets of less length than the spacing of the forms on the strip, and actuating means for operating the severing means in synchronism with the advancement of the strip.

24. The herein described method of dividing a continuous strip bearing a succession of longitudinally spaced printed legends into individual sheets of less length than the relative spacing

of the legends upon the strip, including progressively advancing the strip past a severing position and doubly severing the strip transversely on relatively spaced parallel lines intermediate succeeding imprinted legends thereon.

25. The herein described method of dividing a continuous zigzag folded strip bearing a succession of longitudinally spaced printed legends into individual sheets of less length than the relative spacing of the legends, including progressively advancing the strip past a severing position and doubly severing the strip transversely on relatively spaced parallel lines in proximate

relation with succeeding fold lines between successive folds of the zigzag formation in synchronism with the advancement of the strip, at least one of the lines of severance being offset relative to each fold line to shorten the corresponding fold to less length than the original spacing of the legends borne by succeeding sheets.
